UNITED STATES PATENT OFFICE

2,255,926

ELECTRICAL APPARATUS

Dietrich Müller-Hillebrand, Halensee, and Max Proschmann, Siemensstadt, Germany, assignors to Westinghouse Electric & Manufacturing Company, East Pittsburgh, Pa., a corporation of Pennsylvania

Application February 18, 1939, Serial No. 257,154
In Germany February 19, 1938

8 Claims. (Cl. 200—163)

This invention relates to improvements in electrical apparatus and more particularly to high current carrying devices in the form of bus bar structures, fuses, switches and the like. Heretofore considerable difficulty has been encountered in securing low resistance contacts between separable sections or parts of an electrical conducting system due to misalignment of the cooperating contact surfaces. In practice, the cooperating contact surfaces can seldom, if ever, be machined and aligned with sufficient accuracy to provide a contact area of sufficient size to prevent unduly high current densities.

The problem of obtaining aligned cooperating contact surfaces is rendered more complex in electrical systems designed to carry large currents due to the requirement of conductors of large cross-section which consequently possess considerable rigidity. Conductor rigidity, however, is desirable from the standpoint that it offers self-support.

It is, therefore, an object of this invention to provide a conducting member for high current electrical apparatus which possesses the desired rigidity to be self-supporting, but which has a flexibility such that portions thereof are readily made to engage and cooperate with an associated contact surface.

Another object of this invention is to effect a saving in material used in electrical apparatus by increasing the current carrying capacity of the conducting members without increasing the cross-sectional area and without impairing the longitudinal rigidity of the conducting members.

A more specific object of the invention is the provision of cooperating contact members for electrical apparatus, at least one of which is rendered flexible to a degree to enable it to readily conform to the contour of the other member.

Other objects and advantages relate to the particular structures for carrying out our invention and will appear more fully in the following description when read in connection with the accompanying drawing, in which:

Figure 1 is a side elevational view showing the principles of our invention applied to a fuse structure;

Fig. 2 is an end view of the fuse structure shown in Fig. 1;

Fig. 3 is an elevation view showing our invention embodied in a disconnect switch structure;

Fig. 4 is an end view of the structure shown in Fig. 3; and

Figs. 5 and 6 are, respectively, elevational and

end views of a modified form of contact structure embodying the principles of our invention.

Referring to Figs. 1 and 2 of the drawing, the reference numeral 7 designates a cartridge fuse having a cylindrical body portion 9 of insulating material and a pair of metallic collars or ferrules 11 disposed on opposite ends thereof. Each of the ferrules 11 has a corrugated blade projection 13 extending therefrom. The blade projections 13 are adapted to be seated between a pair of spaced parallel plate members 17 constituting a contact jaw 19. Each contact jaw 19 is provided with a threaded terminal stud 21 which serves to secure the contact jaws to an insulating panel 23, and also provides a terminal for external circuit connections.

The electrical circuit between the two metallic ferrules 11 is completed by a fusible element of conventional form (not shown) within the cylindrical body portion 9.

It should be noted that the blade projections 13 are of corrugated form which provides a series of line contacts between the blade portions 13 and the plate members 17 of the contact jaws 19. The blade portions 13 may, therefore, be constructed of relatively thin flexible material without impairing the rigidity thereof in a direction at right angles to the corrugations. The corrugated structure, however, does not impair the torsional flexibility of the blade portions 13, so that these portions are free to conform themselves to the engageable contact surfaces of the jaw members 19 irrespective of the alignment within predetermined limits of the jaw members.

The grooved or corrugated form of blade member increases the current carrying capacity of the member in that it provides greater surface area for cooling purposes for a given external dimension.

Obviously when a blade portion 13 is inserted between the relatively rigid plate members 17 of the contact jaws 19, and since the blade portions 13 are designed to fit tightly between the plate members 17 upon insertion of the blade portions 13, the corrugations thereof will tend to be flattened out to provide a plurality of spaced line contacting portions under pressure. In the event there are any irregularities or unevenness in the inner contact surfaces of the plate members 17, such defects will be compensated for by virtue of the fact that certain of the corrugations will then be flattened out more than others. This action will provide, within certain limits, for a substantial line contact portion at each of the blade corrugations.

In Figs. 3 and 4 the principles of our invention are shown applied to a disconnect switch consisting of a pair of contact terminals 27 and 29 mounted upon spaced insulators 31 and 33. The insulators 31 and 33 may be carried by a suitable base or support 35. The contact terminals 27 and 29 are bridged by a pair of blade elements 37, and are preferably hinged to the contact terminal 29 by the bolt 39 passing therethrough. Each of the blade elements 37 are preferably of corrugated form, as shown, and are drawn into contacting engagement with the contact terminal 29 by the bolt 39 and the washers 41. The blades 37 also make contacting engagement on opposite sides of the contact terminal 27, and are maintained in clamping engagement with the terminal 27 by a bolt 43 passing transversely through the blade elements. A notch 45 extending inwardly from the outer edge of the contact terminal 27 provides the necessary clearance for the tensioning bolt 43, thereby permitting the blade elements 37 to be swung about the bolt 39 as a pivot to the open and closed position. In order to facilitate the movement of the blade elements 37, a plate 41 is provided secured in any suitable manner to the blade elements and provided at its outer end with an aperture 49 for the reception of a hookstick, by which means the switch may be manually operated.

From the foregoing it is clear that the corrugated form of blade elements 37 provides a switch blade structure which has the requisite rigidity longitudinally of the blade elements, and also sufficient torsional flexibility to enable the blade elements to make a series of line contacts with the contact terminals 27 and 29. Thus in the event that the contact terminals 27 and 29 should become displaced so as to be out of alignment, the misalignment within predetermined limits will not prevent the obtaining of a good contact between the blade elements and the contact terminals.

In Figs. 5 and 6 a further application of our invention is shown, and comprises a corrugated blade-like contact member 51 carried by a stationary support 53. A movable contact 55 having a bifurcated portion 57 is adapted to make sliding engagement with the stationary contact member 51. Movement of the contact member 55 into and out of engagement with the stationary contact 51 may take place longitudinally of the member 55 or in a direction at right angles to the longitudinal axis thereof. In this instance, as set forth in the previous illustrations, the corrugated contact blade is flexible about an axis parallel to the corrugations so as to provide a series of line contacts with the cooperating contact surfaces.

The corrugated blade elements 13, 37 and 51, described in connection with the several figures of the drawing, may be formed of conducting material in any suitable manner as, for example, by bending, rolling or drawing sheet material of suitable thickness or extruding the metal through suitable dies. In instances where the saving of material and the cost of production is of minor importance the corrugated conductors may be formed by machining slots or grooves in conductors of regular form.

Although we have shown and described several specific applications of our invention, it is to be understood that the same are for the purpose of illustration, and that we do not wish to be limited thereby except as set forth in the appended claims.

We claim as our invention:

1. In electrical apparatus, an elongated flexible bridging member of a thickness which is small as compared with its width and which has at least one side thereof longitudinally grooved for increasing its torsional flexibility about a longitudinal axis and for providing at least one convex limited area contact surface.
2. In a circuit making and breaking device, a pair of spaced contact means, and a movable bridging member of flexible material for interconnecting said spaced contact means, said bridging member having sinuous contact portions for engaging said contact means, to rigidify said contact portions at least in one direction but being flexible in at least another direction to provide a more accurate alignment between said contact portions and said contact means.
3. In a circuit making and breaking device, a pair of spaced contact means, a relatively thin flexible blade member normally connecting said contact means and movable into and out of engagement with at least one of said contact means, said blade member being corrugated longitudinally throughout the width thereof on at least one side for providing torsional flexibility of said blade member about a longitudinal axis, and increasing the rigidity of said blade member in a direction at right angles to the corrugations.
4. A circuit making and breaking device comprising a pair of spaced terminals, a pair of blade elements hinged to opposite sides of one of said terminals for swinging movement into and out of engagement with the other terminal, and means for clamping said blade elements into engagement with said other terminal, said blade elements having longitudinally extending slots for rendering said elements torsionally flexible about a longitudinal axis to enable said clamping means to align the blade elements with said other terminal.
5. A circuit making and breaking device comprising a pair of spaced terminals, a pair of blade elements hinged on opposite sides to one of said terminals for swinging movement into and out of engagement with the other terminal, and means drawing said blade elements toward each other into contacting engagement with the opposed sides of said terminals, said blade elements being corrugated throughout their length to provide a series of substantially line contacts with the opposed sides of said terminals.
6. In electrical apparatus, a current carrying elongated flexible bridging member having longitudinal corrugations extending substantially the entire length thereof to provide a torsionally flexible bridging member about a longitudinal axis, but which is substantially rigid with respect to a force applied to said bridging member in the plane of said corrugations and at an angle thereto.
7. In electrical apparatus, a thin flexible current carrying bridging member having rounded corrugations on opposite sides thereof to stiffen the same and provide a plurality of spaced substantially line contact portions at each end thereof.
8. In electrical apparatus, a pair of spaced terminal members, each of said members having a contact jaw, each contact jaw comprising a pair of relatively rigid spaced parallel plate members, an elongated bridging member having cooperating relatively thin contact surfaces which are adapted to be inserted between both

pairs of said spaced parallel plate members to complete an electrical circuit through said terminal members, said relatively thin contact surfaces having a plurality of spaced longitudinal slots for increasing the torsional flexibility thereof about a longitudinal axis to provide for a more

intimate contact between the contact surfaces of said bridging member and said contact jaws despite contact surface irregularities and misalignment of said contact jaws.
